United States Patent Office

Des. 213,331
Patented Feb. 18, 1969

213,331

PITCHER

Marvin G. Yutzey, Moundsville, W. Va., assignor to Morgantown Glassware Guild, Inc., Morgantown,
W. Va.

Filed Dec. 20, 1967, Ser. No. 9,862

Term of patent 14 years

U.S. Cl. D44—21

Int. Cl. D7—01

FIG. 1

FIG. 3

I claim:

The ornamental design for a pitcher, as shown.
